CLAIM

The ornamental design for a container cap, as shown and described.

DESCRIPTION

FIG. 1 is a perspective view of a container cap showing my new design;

FIG. 2 is a front plan view thereof;

FIG. 3 is a front plan view of a container cap showing my new design;

FIG. 4 is a rear plan view thereof;

FIG. 5 is a side plan view thereof;

FIG. 6 is a top plan view thereof;

FIG. 7 is a bottom plan view thereof; and,

FIG. 8 is a perspective partially cross-sectional view thereof with half cutout.

The broken line showing of environment is for illustrative purposes only and forms no part of the claimed design.
